UNITED STATES PATENT OFFICE

LYNDON W. JOYCE, OF GREENSBORO, NORTH CAROLINA, ASSIGNOR TO JOYCE-VENNING MANUFACTURING CO., INC., OF GREENSBORO, NORTH CAROLINA, A CORPORATION OF DELAWARE

MANUFACTURE OF SUSPENDERS

Application filed November 8, 1930. Serial No. 494,378.

This application is a continuation-in-part of my application, Serial No. 486,475, filed October 4, 1930, and the structure which it discloses relates to the manufacture of suspenders and like articles, and proposes a novel method by which the slide parts and the suspender web or strap, are co-operably laid together with the suspender web folded to form the adjustable portion which receives the button engaging loop, and folded with the slide parts in such arrangement that by the single application of pressure to the folded formation, the slide parts are assembled into an integral unit with the suspender web inserted therethrough and in operative adjustable relation to the slide.

The advantages of the new method are primarily a saving of time since by the old operation the suspender web must be threaded under and over and under the several transverse elements of a preformed slide by hand. Threading the web manually through the slide is slow work and necessitates that considerable room be provided between the middle bar and the sides of the slide frame. This is the cause of excessive looseness of the adjustment of the web in the finished slide. By the present method the sides of the slide frame may fit closer to the middle bar and in consequence, a more snug adjustment of the web is possible with less chance of its slipping.

A variant of the method includes the step of first securing, by a preliminary pressing operation, the free end of the suspender web in a trough formed on the lower side of the middle bar, then allocating the middle bar with the suspender web therein retained, in position relative to the frame and the web folds, in the manner above described, and unitarily assembling the slide by pressure, with the web in operative position as described.

With the above and other objects in view the process of the present invention is illustrated in the accompanying drawings in which:

Figure 1 is a view of the parts in assembled relation ready for pressing the slide parts together;

Figure 2 is a similar view in that form of

the invention in which clamping the end of the web in the slide is not employed;

Figure 3 is a perspective view illustrating the elements of the slide and a completed slide;

Figure 4 is a bottom plan view of the assembled slide and suspender web;

Figure 5 is a cross section taken along the line 5—5 of Figure 4; and

Figure 6 is a section taken along the line 6—6 of Figure 4.

Referring now in detail to the several figures, and first adverting to that form of the invention disclosed in Figure 1, the reference character 1 represents a completed slide, its component parts being indicated at 2 and 3, 2 being referred to in the present specification as the frame and 5 as the middle bar. Assembled slides such as those shown at 1 in Figure 3, are old in the art with the exception, so far as known of the dihedral trough, and are purchased or made by suspender manufacturers as a separate and complete article of manufacture. The suspender web is ordinarily assembled with respect to the complete slide by passing a free end of the web under the side 4 of the frame over the middle bar 5, under the side 6 of the frame, drawn through to a sufficient distance to form the fold which retains the button holding loop of the suspender and the free end then drawn back and inserted through the slide in such a way as to be within the fold which holds said loop.

As has been stated above, the threading of the web through the slide is quite time consuming, and the sides 4 and 6 must be spaced quite some distance from the middle bar 5 in order to facilitate the threading of the web.

The present invention employs the frame 2 and the middle bar 5 unassembled, and preferably, although not necessarily employs the dihedral trough 7 to finish and retain the free end of the web.

The sequence of the process steps can be readily understood from Figure 1. Where the end of the web is to be clamped within the slide the free end 8 of the web is first inserted into the dihedral trough of the middle

bar 5, and the sides of the trough pressed clampably upon said web. The web is then folded back beneath the middle bar and folded upon itself as indicated at 9 to receive the 5 button engaging loop 10. The upper fold of the web is brought back and laid across the top of the middle bar. The frame is then laid down upon the top fold of the web in superposed relation to the middle bar. The 10 opposite sides of a press are then brought to bear upon the interleaved portions of the web and slide thus assembled, and by application of pressure the frame is pressed firmly down upon the upper fold of the web and 15 the lugs 11 of the middle bar are turned over and pressed clampingly against the end portions 12 of the frame firmly uniting the middle bar and frame into an integral structure the same as is shown at 1 in Figure 3, the 20 web being thereby maintained in operative adjustable position in the slide with the free end thereof caught in the trough of the middle bar 5. The clamped position of the parts is shown in Figures 4, 5 and 6 and does not 25 differ materially from the position of the parts in a suspender and slide assembled by the old and more tedious method. Since no threading of the web through the slide has been necessitated, the width of the space indicated at 13 in Figure 5 between the sides of 30 the frame and the middle bar of the slide may be made less than in the known construction so that the slideable portion of the web is more firmly held against displacement.

35 As will be noted at 14 in Figures 5 and 6, the lower part of the press which affixes the middle bar to the free end of the web may be provided with die projections for indenting the under-fold of the middle bar thereby producing internal teeth which dig into the suspender web and firmly hold the free end thereof against displacement.

40 Where the dihedral trough or its equivalent is not employed, the process is carried out by the web and the component parts of the slide being made ready for the press by first laying flat a length of web adjacent the free end. The middle bar is laid upon this and the free end folded over the middle bar. 45 The portion first laid down is then folded over at a suitable point, to engage the suspender loop and then extended back so as to overlie the middle bar and the free end portion which lies above it. The frame is then 50 placed upon the uppermost layer of the web in proper position relative to the middle bar and the press is then applied in the same manner as previously described.

55 While I have in the above description illustrated my novel method in connection with certain specific forms of slide and specific arrangements of the suspender web, it is to be understood that the breadth of the invention is not to be determined by the details 60 of construction as shown, but by a fair and

broad interpretation of the terms of the appended claims.

What I claim is:

1. Method of assembling a suspender web and slide in operative relation comprising, 70 pinching the free end of a suspender web in a trough-shaped fold of a middle bar, arranging the frame and the middle bar of the slide in unassembled relation, and in inter-folded relation to the suspender web, with the free 75 end of said web secured to said middle bar as defined, the suspender web being folded so as to form the adjustable fold for a button engaging loop, and pressing together the parts of both slide and web, inter-folded as defined, 80 so as integrally to assemble the slide parts with a fold of the web slidably disposed between said frame and middle bar.

2. Method of assembling a suspender web and slide in operative relation comprising, 85 arranging the component parts of the slide, unassembled, in inter-folded relation to the suspender web, the latter being folded so as to form the adjustable fold for a button engaging loop, and pressing together the parts 90 of both slide and web inter-folded as defined so as integrally to assemble the slide parts with a fold of the web slidably disposed therebetween.

In testimony whereof I affix my signature. 95
LYNDON W. JOYCE.
